UNITED STATES PATENT OFFICE.

ANDREW SMITH, OF MILWAUKEE, WISCONSIN.

OIL PAN FOR INTERNAL-COMBUSTION MOTORS.

Application filed November 13, 1923. Serial No. 674,542.

To all whom it may concern:

Be it known that I, ANDREW SMITH, a citizen of the United States, and resident of Milwaukee, in the county of Milwaukee, and State of Wisconsin, have invented certain new and useful Improvements in Oil Pans for Internal-Combustion Motors; and I do hereby declare that the following is a full, clear, and exact description thereof.

10 This invention relates to oil pans and is particularly directed to an oil pan for an internal combustion engine.

In internal combustion engines, it is customary to provide an oil intake within the crank case adjacent the oil pan, so as to permit the circulation of oil by any suitable means. Difficulty has been experienced in this arrangement of parts in that on the one hand if the oil intake is located high enough 20 to avoid the entraining of water and sediment which has collected beneath the layer of oil that as soon as it is slightly lowered this intake fails to reach the oil and, on the other hand, if the intake is placed low enough to insure at all times a supply of oil the sediment and water will be entrained and drawn into this intake.

This invention is designed to overcome the above noted defects, and objects of such 30 invention are to provide an oil pan which is so associated with the intake and which is so constructed that oil will be constantly available at the intake and the entrance of water or sediment will be wholly avoided.

35 Further objects are to provide an oil pan with a sediment chamber which is provided with a movable cover adapted for external manipulation so that when the engine is not running the cover may be raised and the sediment and water collected in the sediment chamber, and when the engine is running, the cover may be lowered to thus trap and shut out the sediment and water, and to thus prevent its passage into the oil intake.

An embodiment of the invention is shown in the accompanying drawings, in which:

50 Figure 1 is a longitudinal sectional view through the lower portion of a crank case showing the oil pan and its associated parts in position, such figure corresponding to a section on the line 1—1 of Figure 2.

Figure 2 is a transverse sectional view 55 on the line 2—2 of Figure 1.

Figure 3 is an enlarged fragmentary detail of the strainer portion of the oil intake.

The crank case 1 has bolted thereto a downwardly slanting oil pan 2. A sediment 60 chamber 3 is provided with upwardly flaring walls which join the oil pan 2 and thus the sediment chamber opens into the lowest portion of the oil pan. This sediment chamber is provided with a cover 4 which is 65 equipped with slanting sides 5 which, as shown, may consist of an inwardly turned flange adapted to fit the slanting walls 3 of the sediment chamber. A cam 6 is located below the cover 4 and is rigidly carried upon 70 a shaft 7 which projects outwardly through the sediment chamber and carries at its outer end a lever 8. This lever is connected by means of a rod 9 to any suitable manually manipulable means located at some accessible point on the automobile such as the dashboard, for instance. The intake 10 for the oil pump terminates a slight distance above the cover 4 and is provided with a hollow cylindrical strainer 11 formed of wire 80 mesh with closed upper and lower and side walls, as shown in Figure 3. A hood 12 in the form of a cone is attached to the intake 10 and extends outwardly and downwardly therefrom to a plurality of supporting fins 85 13 secured both to the hood and to the oil pan 2.

Inwardly extending, downwardly turned fingers 14 are provided and are carried adjacent the lower portion of the hood, as illustrated in Figures 1 and 2. These fingers are adapted to engage the slanting upper surface of the cover 4 and to thus center the cover when it is raised by the cam member 6 and space it from the marginal edges 95 of the sediment chamber 3.

The operation of the apparatus is as follows: When the engine is running the cover 4 is in the position shown in Figure 1 and thus closes the sediment chamber 3 and prevents the circulating oil from stirring up any sediment collected in the chamber 3. However, when the car is put away for the night, for instance, or otherwise not in use, the operator merely lifts the cover 4 upwardly by operating the rod 9, thus posi-

tioning the cover, as shown in Figure 2. This permits any water and any sediment which the oil has gathered to settle downwardly along the slanting bottom of the oil pan 2, and to travel into the sediment chamber 3. When the car is again to be used, the operator manipulates the rod 9 and moves the cam member 6 into the position shown in Figure 1, thus allowing the cover to move downwardly closing the sediment chamber 3.

It is to be noted that even if sufficient water was collected by the sediment chamber to freeze, that, nevertheless, the tapered upward walls of such chamber would prevent the expanding ice from damaging any portion of the apparatus, and in addition to this, the engine could be operated, as none of the active portions of the oil pan or associated parts would be clogged by this freezing. Any suitable means such as the removable plug 15 (see Figure 2) may be provided for draining the sediment chamber 3 at such times as this operation may become necessary.

It is to be noted that the conical hood 12 extends beyond or overhangs the cover 4 and is spaced upwardly therefrom so that any settling material will be deflected away from the cover and to a point adjacent the marginal edges of the sediment chamber 3.

It will thus be seen that a very effective sediment chamber and pump intake apparatus have been provided which will cooperate with an oil pan in a simple and effective manner.

It will also be seen that the operation of the apparatus may be from a remote point and may be easily effected with scarcely any effort on the part of the operator and without calling upon him to manipulate greasy or soiled portions of the engine.

Although the invention has been described in considerable detail, it is to be

understood that the invention may be variously embodied and is, therefore, to be limited only as claimed. 45

I claim:

1. In a device of the class described, the combination of a downwardly slanting oil pan, a sediment chamber opening into the lowest portion of said oil pan, a cover adapted to normally cover the upper portion of said sediment chamber, externally accessible means for elevating said cover without disturbing said sediment chamber, and centering means for engaging the margins of said cover when elevated to hold said cover spaced from the upper margin of said sediment chamber. 50 55

2. The combination of a downwardly tapering oil pan for an engine, a sediment chamber opening upwardly into the lowest portion of said oil pan, a cover normally closing the upper portion of said sediment chamber, an oil intake located above said cover, a hood having downwardly slanting sides overhanging and spaced above said cover, and externally manipulable means for elevating said cover. 60 65

3. The combination of a downwardly tapering oil pan for an engine, a sediment chamber opening upwardly into the lowest portion of said oil pan, a cover normally closing the upper portion of said sediment chamber, an oil intake located above said cover, a hood having downwardly slanting sides overhanging and spaced above said cover, externally manipulable means for elevating said cover, and means for guiding said cover when elevated to hold said cover centrally beneath said hood and spaced from the margin of said sediment chamber. 70 75 80

In testimony that I claim the foregoing I have hereunto set my hand at Milwaukee, 85 in the county of Milwaukee and State of Wisconsin.

ANDREW SMITH.
